REFRIGERATED SHELF UNIT FOR OPEN TOP REFRIGERATED DISPLAY CASES

Julius H. Rainwater, Atlanta, Ga., assignor to The Warren
Company, Inc., Atlanta, Ga., a corporation of Georgia

Filed Feb. 28, 1963, Ser. No. 73,752

Term of patent 14 years

(Cl. D80—11)

Fig. 1.

Fig. 2.

Fig. 3.

I claim:

The ornamental design for a refrigerated shelf unit for open top refrigerated display cases, as shown and described.
